TUFT PILE FABRIC LOOM

Edwin W. Stone, Longmeadow, Mass., assignor to
Bigelow-Sanford Carpet Co., Inc., Thompson-
ville, Conn., a corporation of Massachusetts

Application August 12, 1933, Serial No. 684,799

5 Claims. (Cl. 139—7)

This invention relates to looms for weaving tuft pile fabrics, and more particularly, though not exclusively, to tuft pile fabrics wherein the pattern of the pile surface is reproduced upon the back.

Tuft pile fabrics such, for instance, as Axminster and like carpets and rugs, as ordinarily woven present objectionable characteristics, especially where the pattern of the pile surface is to be reproduced upon the back. The first of these is due to the looseness in the weave of the backing fabric with consequent liability of the tuft yarns being detached during use. Second, the warp threads and consequently pile forming tuft yarns which are placed about a holding weft shot between the warp threads become distorted during weaving, due to the fact that the warp threads are not maintained in their established pitch or laterally separated relation.

One of the objects of the present invention is to provide a tuft pile fabric loom with means whereby the objections heretofore existing in the resulting fabric are overcome, a close weave effected in the backing fabric and a uniform relation maintained in the warps and pile forming tufts.

The invention and novel features thereof will best be made clear from the following description and accompanying drawings of one good form thereof.

In the drawings:—

Fig. 1 is a sectional elevation of a portion of an Axminster loom provided with the present invention;

Fig. 2 is an enlarged detail of the transversely extending bar for controlling the pitch relation of the warp threads and supporting the loops of the pile forming tufts;

Fig. 3 is a view similar to that of Fig. 1 showing the lay in its forward position beating up a holding weft shot for the tufts;

Fig. 4 is a similar view showing the lay and the transversely extending bar in their back positions;

Fig. 5 is a similar view with some of the parts omitted showing the rear leg of the tuft yarns as being turned upwardly between the warp threads;

Fig. 6 is an enlarged detail of the transversely extending bar showing more particularly the relation of the threads and bar during weaving; and

Fig. 7 is a view similar to Fig. 5 showing a slightly modified form of the invention.

The loom frame may be of usual and well known construction appropriate for the support of the operating parts but it as well as other details of the Axminster loom that are well known, are not herein shown and described, since the details of such features form no part of the present invention.

The lay 1 is mounted on the loom frame as usual, for its beat up movements which are imparted thereto by the usual form of lay operating mechanism, and mounted upon the top portion of the lay is the reed 2.

Secured to the loom frame in fixed position is the breast plate 3 over which the fabric *a* passes as it is woven, as usual.

The tuft yarns 4 are introduced at the weaving point by the usual tube frames 5, only one of which is shown, and the transferring mechanism for taking a tube frame from the carrier or chain to the weaving point is not illustrated as it is well known.

The cutters 6 and 7 may likewise be of usual construction to cut or part the tuft yarn after it has been looped about a holding weft shot and such cutters may be operated by any usual well known type of mechanism.

Mounted upon the bracket 8 secured to the loom frame is a rock shaft 9 which constitutes the axis about which arms 10 turn, and in order that the movement of parts may be facilitated without too much friction ball bearings 11 are preferably employed. Secured to the hub portion of the arms 10 is a lever 12 to which is secured one end of a spring 13 at 14, the other end of the spring being secured to a proper fixed point 15 shown, in the present instance, as being an eye bolt secured to the breast plate, and the spring 13 acting through the lever 12 normally tends to move the arms 10 rearwardly.

Mounted upon the arms 10, one preferably at each side of the loom, is the transverse bar 16, the details of which will presently be described.

As hereinbefore noted, the spring 13 normally acts to turn the arms 10 rearwardly about their axial support and to limit such movement rearwardly the lever 12 is provided with an adjustable stop 17 which, when the arms and transverse bar are in their rearward position, engages the end portion 18 of the breast plate thereby limiting the movement rearwardly.

The arms 10 are provided with an adjustable bunter 19 which is shown in the preferred form of the invention as a screw bolt held in adjusted position by the lock nut 20, so that on the beat-up movement of the lay the bunter 19 will engage

the lay beam at 21 and move the arms and transverse bar frontwardly.

As a modified form of this feature of the invention Fig. 7 shows the bunter as a roller 22 mounted on an adjustable bracket 23 secured to the arms 10, a slot 24 being provided through which passes a screw bolt 25 so that by loosening the latter the bracket 23 and perforce the roller 22 may be adjusted backwardly or frontwardly 10 in accordance with the desired conditions. In connection with the modified form of bunter the lay may be provided with a cam portion 26 shown as carried by a bracket 27 secured to the lay beam.

15 The bunter either 19 or 22 by engagement with the lay on its beat up movement causes the arms 10 and the transverse bar 16 to be moved frontwardly just prior to the time when the reed 2 might otherwise contact with the rear end of the 20 bar 16.

The transverse bar 16 is of novel construction adapting it for maintaining the warp threads in their established pitch relation during weaving and further adapting it for the support of the 25 loops of the tuft yarns after they have been passed about the holding weft shot.

The transverse bar 16 has a series of grooves 28 which extend from the rear edge of the bar 16 frontwardly and as shown terminate short of the 30 front edge portion of the bar. The grooves 28 are laterally spaced in accordance with the established warp pitch or lateral separation of the warp threads.

When the arms 10 and consequently the transverse bar 16 are moved back and forth between the lay and breast plate, as hereinbefore described, the lower walls of the grooves 28 move in an arcuate path 29 which, as indicated, is tangential to the plane of the warp threads, the 35 result being that when the transverse bar is given its described movements the warp threads will engage the grooves 28 in the transverse bar and thereby be held in their established pitch or laterally separated relation.

40 As more clearly indicated in Fig. 6 the grooves 28 in the transverse bar 16 have the side walls 30 and 31 converging downwardly so that the warp threads engage the upper widened portion 45 of the grooves during the movement of the cross bar and the warp threads will be guided into the grooves and restored to their proper established pitch relation should they have been disturbed from this condition.

The top portion of the walls or teeth which 50 separate the grooves and which will be hereininafter identified as "lands", is made of sufficient extent or flattened as at 32 for the support of the loops of the tuft yarns where they pass about the holding weft shot.

55 Inasmuch as the grooves 28 have their greatest depth at the rear edge portion of the transverse bar, and the transverse bar is given a rocking movement about the shaft 9 as a center, the "lands" of the grooves will be raised above the warp threads lying in the grooves so that the 60 loops of the tuft yarns will be firmly held about the holding weft shot during the beat-up movements of the binding weft shot.

65 In order that the downwardly extending leg of the tuft yarn 4 may be turned upwardly between the warp threads and about the back holding weft shot a comb 33 is preferably employed and as shown, it is mounted on the bars 34 supported on the rock shaft 35 and given appropriate

movements, as usual, when the tuft yarn has been engaged by the holding weft shot.

In the cycle of the loom operation the tuft yarns 4 will be introduced at the weaving point by the tube frames 5, as in Fig. 1, whereupon a back holding weft shot is introduced into the shed and beaten to place, as illustrated in Fig. 3, and as the lay goes back the transverse bar 16 likewise moves backwardly and the "lands" thereof turn the lower leg of the tuft yarns into a substantially 10 horizontal position, as indicated in Fig. 4. The comb 33 then acts to turn the horizontal leg of the tuft yarn upwardly about the holding weft shot, as indicated in Fig. 5, so that when the binding weft shot is introduced and beaten to 15 place, the loops of the tuft yarns which are then supported upon the "lands" of the grooves in the transverse bar hold or clamp the loops in place to permit the binding weft shot to draw such loops tightly about the holding weft shot. 20

Thus a tuft pile fabric is produced having a pattern on the back corresponding to the pile surface, the backing fabric is tightly woven, the warp threads are maintained in their established pitch relation, and the tuft yarns which pass about a 25 holding weft shot between the warp threads are uniformly spaced throughout the width of the fabric being woven.

What is claimed is:—

1. In a tuft pile fabric loom, the combination 30 of a breast plate over which the fabric passes as it is woven, a transversely extending bar rearward of the breast plate provided with warp receiving grooves for maintaining all of the warp threads in their established warp pitch relation 35 and lands between the grooves for engaging and supporting the loops of the pile forming yarns above the bottom of the grooves, and means for moving the bar towards and from the breast plate in a curved path tangential to the plane of the warp threads that the warp threads may engage the grooves and the pile forming yarns may have their loops supported on the "lands" between the grooves in laterally uniform spaced relation. 40

2. In a tuft pile fabric loom, the combination 45 of the lay, a breast plate over which the fabric passes as it is woven, a transverse bar between the lay and breast plate having a series of lands for engaging and supporting the loops of pile forming tufts and warp receiving grooves for holding all of the warp threads in their established pitch relation, and means for imparting bodily movements to the transverse bar back and forward between the lay and breast plate in an arcuate 55 path tangential to the warp plane that the warp threads may be received in said grooves to maintain their pitch distance and the pile forming tufts may be supported on the "lands" between the grooves. 60

3. In a tuft pile fabric loom, the combination of the lay, a fixed breast plate, a transverse bar between the lay and breast plate provided with warp receiving grooves gradually diminishing in depth from the rear edge of the bar frontwardly for holding all the warp threads in their established pitch relation and having tuft loop supporting "lands" between the grooves, and means for moving the bar bodily between the lay and breast plate in an arcuate path tangential to the warp plane that the warp threads may be engaged with the grooves of the bar and be held in their pitch relation and the loops of the pile forming tufts may be supported by the lands between 70 75

- the grooves when passed about a holding weft shot.
4. In a tuft pile fabric loom, the combination of the lay, a breast plate, a transverse bar mounted for rocking movement between the lay and breast plate and provided with a series of grooves and "lands", the former having downwardly converging side walls for directing the warp threads into the grooves to maintain the warp threads in their established pitch relation, and the "lands" having tuft loop supporting portions, and means for moving the transverse bar between the lay and breast plate in a curved path tangential to the warp plane.
5. In a tuft pile fabric loom, the combination of the lay and breast plate, a bar extending transversely of the loom between the lay and breast plate and provided with grooves and "lands" extending transversely of the bar, arms mounted for rocking movement about an axis below the breast plate and supporting the said bar, a lever connected to said arms, a spring connected to said lever and normally acting to move the arms and bar rearwardly, and a bunter on one of the arms adapted to be engaged by the lay on the beat up to move the arms and bar forwardly.

EDWIN W. STONE.
